WO 2017120665 7/2017

Primary Examiner — George D. Kirschbaum

Assistant Examiner — Lillian Windham

(57) **CLAIM**

I claim the ornamental design for a level-correcting gauge block, as shown and described.

DESCRIPTION

FIG. 1 is a left side view of the level-correcting gauge block.

FIG. 2 is a right side view of the claimed design.

FIG. 3 is a top view of the claimed design.

FIG. 4 is a bottom view of the claimed design.

FIG. 5 is a front view of the claimed design.

FIG. 6 is a rear view of the claimed design; and,

FIG. 7 is a perspective view of the claimed design.

1 Claim, 4 Drawing Sheets(56)
